WILLIAM S. COOPER, OF PHILADELPHIA, PENNSYLVANIA.

Letters Patent No. 85,909, dated January 19, 1869.

IMPROVED WATER-CLOSET VALVE.

The Schedule referred to in these Letters Patent and making part of the same.

To all whom it may concern:

Be it known that I, WILLIAM S. COOPER, of Philadelphia, in the State of Pennsylvania, have invented a new and useful Improvement in Water-Closet Valves; and I do hereby declare that the following is a full, clear, and exact description of the same, reference being had to the accompanying drawings, and letters of reference marked thereon, making a part of this specification, in which—

Figure 1 is a longitudinal vertical section of the valve-case through the ports, exhibiting a side elevation of the plunger, spring, and hollow stem attached to the bottom-piece; and

Figure 2 is a longitudinal vertical section through the plunger A, showing the shape of the bevelled flange l.

To enable those skilled in the art to make and use my invention, I now proceed to describe its construction and operation.

Similar letters in the drawings refer to like parts.

This invention consists of a cylindrical plunger, provided with a series of recesses in its outer surface, so arranged that while the plunger is passing through a packing-ring fitting it water-tight, water may be transmitted from one side to the other of said packing-ring, through said recesses; also, of a bevelled flange, forming part of the aforesaid plunger, and operating in connection with a bevelled packing-ring, to make a watertight joint, as will hereinafter more fully appear.

A represents a metallic casing, of tubular form, provided with outlet and inlet-ports, a a', and a conical top, with a circular orifice at the upper portion thereof, in which orifice is a plug, b, fitted to slide freely, to the bottom of which is attached a circular diaphragm of rubber, b', the edges of which are firmly confined between the conical top of the casing A and the upper end of said casing.

The outlet and inlet-ports a a' open into the casing, about opposite each other, and from the inner surface of said casing projects a circular flange, c, about at the centres of the ports a. a'.

To the inner surface of the flange c is firmly attached a packing-ring, c', projecting a short distance below the flange c, said packing-ring having a straight inner surface and a bevelled outer surface, and being held firmly in position by a nut.

To the bottom of the casing A is screwed an end-piece, d, provided with a hollow stem, d', into which fits a regulating-screw, e, having a hollow slotted stem, e', on its upper end, operating in connection with a water-passage, h, in the hollow stem d', all these last-mentioned parts being described in my patent of March 10, 1868, to which reference is made for a more particular setting forth of their operation, they forming no part of my present invention.

B represents a cylindrical plunger, provided with a series of recesses, i, of a length greater than the width of the aforesaid packing-ring c', and arranged in a regular row around the lower part of the plunger, one or two of said recesses being of greater length than the others.

Said plunger closely fits the packing-ring c', and has four or more standards, k, upon its lower end, which support a disk, k', bearing a packing-ring, k'', upon its periphery, which packing-ring fits closely the inner surface of the casing A.

A flange, l, surrounds the lower end of the plunger B, said flange being inclined upward and outward at its upper edge, or being, in other words, an outward-bevelled flange at its upper side, the object of such beveling being that a tight joint may be made when the flange shuts up around the before-mentioned packing-ring c'.

A spiral spring, m, is interposed between the disk k' and the bottom-piece d, said spring surrounding the hollow stem d'.

Operation.

Suppose the above-described mechanism to be placed in a water-closet, in such position that the descent of the seat, under the weight of one easing himself, shall force the plug b downward. Said plug, as it descends, forces the plunger B downward so far that all the recesses i, except the longer ones, are carried past the packing-ring c'. The surface of the plunger is then in contact with the packing-ring at all points, so that no water can flow between the two, except through the aforesaid longer recesses, during all the time the seat is depressed, by which means all waste of water is prevented during the easing-operation. When the sitter rises, the spiral spring m forces the plunger B upward, so that the recesses i pass the packing-ring c', and during this passage, which takes place slowly, water may pass between the plunger and packing-ring through the recesses. When the plunger rises high enough to bring the bevelled flange l in contact with the bevelled packing-ring c', additional security against the passage of water is provided, as the bevelled part of the flange forces the edge of the packing against the plunger.

Having thus fully described my invention,

What I claim as new, and desire to secure by Letters Patent, is—

The plunger B, with the recesses i and ring or collar c', in combination with the bevelled flange l, as described, and for the purposes set forth.

WM. S. COOPER.
